UNITED STATES PATENT OFFICE.

JOSEPH J. MICHELS, OF SYRACUSE, AND FRANK W. MICHELS, OF EAST SYRACUSE, NEW YORK.

CAR-REPLACER.

1,315,566.

Specification of Letters Patent.

Patented Sept. 9, 1919.

Application filed May 24, 1919. Serial No. 299,629.

To all whom it may concern:

Be it known that we, JOSEPH J. MICHELS and FRANK W. MICHELS, citizens of the United States of America, and residents of 5 Syracuse, New York, and East Syracuse, New York, in the county of Onondaga, in the State of New York, have invented new and useful Improvements in Car-Replacers, of which the following, taken in connection 10 with the accompanying drawings, is a full, clear, and exact description.

This invention relates to certain improvements in car replacers and it is adapted to be used more particularly for replacing 15 street or surface cars on tracks which are substantially flush with the surface of the pavement as in cities and other more or less congested districts where artificial pavements are most common.

20 The main object is to provide coöperative car replacing devices capable of being placed flatwise upon the pavement close to the displaced wheels, irrespective of the relation or proximity of said wheels to the rails upon 25 which they are adapted to travel, and to provide said replacers with spurs or equivalent devices, capable of embedding themselves into the pavement or, if necessary, into the rails under the load or weight of the car riding thereon under any propelling power so 30 that if the displaced wheels are more or less remote from their rails they may be gradually worked up to the rails by repeated use of the replacers until brought into substantially 35 close proximity to said rails to allow the wheels to be replaced directly upon the track.

Another object, in the use of the coöperative devices or replacers, is to enable one of 40 them to be used for crowding the displaced portion of the car toward the rails as the car is propelled upon both the replacers and to utilize the other replacers for alining up the wheels with their respective rails, it being 45 understood that both devices are provided with elevated ribs or supplemental rails for elevating the flanges of the wheels from the ball of the rail as the car is propelled toward the track.

50 Other objects and uses relating to specific parts of the replacing devices will be brought out in the following description. In the drawings—

Figure 1 is a top plan of portions of a

railway track and our improved coöperative 55 replacers in operative position for replacing one of the trucks of the car, the wheels and axles of said truck being shown by dotted line as about to be replaced upon the rails.

Fig. 2 is an enlarged cross sectional view 60 of the same track and replacers in operative position showing also one of the axles and its wheels in operative position for replacement upon the track, the central portion of the axle and intervening portion of the pave- 65 ment between the rails being broken away.

Figs. 3 and 4 are perspective views of the care alining replacer section and the coöperative guide section respectively.

Fig. 5 is a perspective view of a modified 70 form of alining section in which a channel and switch point are substituted for the supplemental rib or rail of the replacer.

In order that our invention may be fully understood we have shown the rails as —a— 75 of a surface railway track in which the balls of the rail are substantially flush with the surface of the pavement as —B— and adapted to receive the wheels as —C— of their car axle —c—. The car replacer comprises co- 80 operative sections 1 and 2 which may be termed respectively, the thrust section and the alining section for the reason that the section —1— serves to thrust the wheels and axle axially while the section —2— serves to 85 aline the wheels with their respective rails. As illustrated in Figs. 1 to 4, inclusive, each section comprises a relatively broad flat plate or base —3— having a central lengthwise raised rib —4— on its upper face preferably 90 integral therewith, since both devices are usually made of cast metal of sufficient strength to enable them to carry the loads for repeated use, said ribs constituting supplemental rails by which the car wheels riding thereon may be raised from the pavement a sufficient distance to carry their flanges above the balls of the track rails —a— when replacing the car upon the track.

The base plates —3— are relatively broad and flat as compared with the ribs —4— and are preferably tapered from their rear ends forwardly so that the rear ends are of greatest breadth or width to better resist the weight of the car in its initial entrance upon the replacer sections, the lower faces of said base plates being flat except that they are provided with hardened steel spurs —5— at

suitable intervals throughout their areas for embedding themselves into the surface of the pavement —B— or into the surface of the rails if they should happen to be registered therewith, the object of which is to prevent slipping or skidding of the replacer sections as the car wheels are riding thereon in the act of replacing the same upon the track. The ribs —4— preferably extend the entire 10 length and beyond opposite ends of their base plates —3— to form what may be termed leads —6 and 7—, the lower faces of which are disposed at substantially the same flat plane as the bottom of the base 15 plates —3— while their upper faces are inclined longitudinally in opposite directions as clearly shown in Figs. 1 to 4, inclusive, to enable the car to ride more easily upon and from the replacer sections. For a similar 20 reason the front and rear ends of the thrust section —1— are beveled to allow the flange of the wheel to ride more easily upon and from the same.

The opposite sides of the rib —4— of the 25 thrust section —1— are preferably parallel and straight from end to end while the opposite sides of the front end of lead —7— of the section —2— are flared along curved lines, the remaining sides of the same rib 30 being parallel and of substantially the same width as that of the section —1—. The object in flaring or curving the opposite sides of the front end of the section —2— is to permit the plates to be reversed side for side in 35 case the car displacement should be at the opposite side of the track from that shown, the active curved side of the lead —7— being usually arranged tangential or nearly so to the inner side of the ball of the rail. 40 so that the flange of the adjacent car wheel will be deflected until alinement with its rail as the car is moved along the replacers, thereby effecting a similar alinement of the 45 opposite wheel through the medium of the connecting axle —c—.

In operation after the car has been brought into sufficiently close proximity to the rails by repeated use of the replacers to 50 enable it to be finally replaced upon the track, the replacers are positioned as shown in Fig. 1 so that the front lead —7— of the section —1— will be directly over the ball of the corresponding rail while the section —2— will be placed so that the tangent 55 point of the inner curved side of its front lead —7— will be nearly directly opposite the front lead —7— of the section —1— while the corresponding front end of the same side of the lead —7— of the section

—2— will be alined with the inner side of 60 the corresponding ball of the rail —a—.

Under these conditions it is evident that as the right hand wheel, Fig. 1, of the car rides upon the rib —4— of the corresponding section —1—, the inner flange will ride 65 against the face of said rib which in turn will thrust the wheels of the axles —c— endwise to the left as the car is moved forwardly, at which time the left hand car wheel will have moved upon and along the 70 rib —4— of the section —2— and by the time the right hand wheel reaches the front end of the lead —7— of the section —1— the left hand wheel will begin to ride against the inner curved side of the lead —7— of 75 the section —2—, these two operations serving not only to position the wheels directly over their respective tracks but will also aline them therewith and cause them to ride upon their respective rails when they leave 80 the leads —7—.

In Fig. 5 we have shown a modified form of alining section —2'— as provided with a pair of lengthwise ribs —4'— in transversely spaced relation to form an intervening 85 groove —8— for receiving the flange of the wheel, the front end of the groove being gradually enlarged or flared to receive a switch point —9— which is pivoted at its front end at —10— to enable its rear end 90 to be moved laterally for guiding the wheel on to the rail, the position of the point depending upon the side of the track to which the car is displaced and at which the replacer is positioned. Otherwise the 95 construction is similar to that previously described for the section —2—.

What we claim is:—

A car replacer comprising a thrust section and an alining section, the thrust section being adapted to be placed in proximity to one of the rails and the alining section in proximity to the opposite rail, each section being provided with a substantially flat and relatively broad base plate and a central lengthwise rib rising from the upper surface thereof, the opposite sides of the thrust section being substantially parallel from end to end while the front end of the rib of the alining section is flared laterally and forwardly.

In witness whereof we have hereunto set our hands this 7th day of May, 1919.

JOSEPH J. MICHELS.
FRANK W. MICHELS.
